(57) **CLAIM**

The ornamental design for a 3 dimensional tic tac toe game, as shown and described.

DESCRIPTION

FIG. 1 is a top plan view of the 3 dimensional tic tac toe game; FIG. 2 is a bottom plan view of the 3 dimensional tic tac toe game;

FIG. 3 is a side elevation view of the 3 dimensional tic tac toe game; and,

FIG. 4 is a perspective view of the 3 dimensional tic tac toe game.

The broken line showing of game pieces is included for the purpose of illustrating portions of the “article” and forms no part of the claimed design.
